UNITED STATES PATENT OFFICE.

CARL L. SHELTON, OF GREENFIELD, TENNESSEE.

COMBINATION BOX AND NEWSPAPER WRAPPER.

Specification of Letters Patent. Patented Nov. 19, 1918.

1,285,429.

Application filed January 25, 1918. Serial No. 213,741.

To all whom it may concern:

Be it known that I, CARL L. SHELTON, a citizen of the United States, residing at Greenfield, in the county of Weakley, State of Tennessee, have invented a new and useful Combination Box and Newspaper Wrapper; and I do hereby declare the following to be a full, clear, and exact description of the invention, such as will enable others skilled in the art to which it appertains to make and use the same.

This invention relates to a combination box and paper wrapper, and an object of the invention is to provide a wrapper having means whereby the wrapper may be employed for securely wrapping a box, newspaper, or a magazine or the like.

A further object of the invention is to provide a wrapper which may be easily constructed for a small cost and sold at a reasonable profit.

A further object of the invention is to provide an improved wrapper particularly adapted for securing and wrapping boxes for facilitating against damage during their transportation through the mails, particularly the parcel post system.

A further object of the invention is to provide a wrapper consisting of one or two sections, the single section being adapted for use in wrapping newspapers and the like, and which single section has scored line on which the section may be severed, whereby the two halves thereof may be connected to the top of a box by adhesive material and their ends secured together by suitable clasps, for wrapping a box.

In practical fields the details of construction may necessitate alterations falling within the scope of what is claimed.

The invention comprises further features and combination of parts as hereinafter set forth shown in the drawings and claimed.

In the drawings:

Figure 1 is a view in perspective of a box, showing the wrapper applied thereto.

Fig. 2 is a sectional view on line 2-2 of Fig. 1.

Fig. 3 is a detail perspective view of a wrapper having a scored or perforated line, and which wrapper is adapted for wrapping newspapers, magazines and the like.

Fig. 4 is a detail perspective view of a wrapper section.

Referring more especially to the drawings 1 designates the body of a wrapper which

may be constructed of any suitable material, preferably heavy paper. This body is provided with a transversed perforated or scored line 2, and on one face of the body on each side of the scored or perforated line, suitable adhesive material 3 may be applied. One end of the wrapper is provided with an aperture or opening 4 having a heavy paper ring reinforcement 5 about its marginal edge. A metallic tab or fastener 6 is provided for the other end of the wrapper. This tab or fastener is T-shaped, and the end portions 7 of the transverse part of said T-shaped fastener are forced through the end 70 of the wrapper and bent as shown to secure the tab to the wrapper. In wrapping newspapers, magazines and the like, the wrapper is first secured to the newspaper (which is rolled) by means of the adhesive material 75 3. The end portions of the wrapper are then passed about the newspaper or the like and the tab passed through the reinforced opening 4 and bent. The end of the wrapper to which the tab is attached is reinforced by a 80 heavy piece of paper 8. In wrapping boxes or the like, as shown in Figs. 1 and 2 the wrapper may be severed on the perforated or scored line 2, subsequently to which the severed end portions may be secured to the 85 side flanges of the cover of the box by the adhesive material 3, and then the other ends of the two sections of the wrapper clasp together by the tab 6, as shown in Figs. 1 and 2. If desired the wrapper for a box may be 90 constructed in two sections originally.

The invention having been set forth what is claimed as new and useful is:—

A wrapper, comprising a blank having co-operating fasteners at its opposite ends, a facing of adhesive material extending transversely of one face of the blank across the middle portion thereof, said blank at its center and across the middle of the facing of adhesive material being provided with a 100 scored line of perforations, whereby the blank may be employed as a newspaper wrapper or severed on said scored line of perforations, whereby the opposite halves of the blank may be employed as box wrappers. 105

In testimony whereof I have signed my name to this specification in the presence of two subscribing witnesses.

CARL L. SHELTON.
